UNITED STATES PATENT OFFICE.

EDWARD E. ZIEGLER, OF PHILADELPHIA, PENNSYLVANIA.

MASSAGE-MACHINE.

976,423.

Specification of Letters Patent. Patented Nov. 22, 1910.

Application filed April 13, 1909. Serial No. 489,694.

To all whom it may concern:

Be it known that I, EDWARD E. ZIEGLER, a citizen of the United States, residing at Philadelphia, in the county of Philadelphia and State of Pennsylvania, have invented 5 certain new and useful Improvements in Massage-Machines, of which the following is a specification.

The present invention relates to massage 10 machines; and particularly to the type in which an electric motor or some similar motive power is employed to drive the main shaft of the massage machine, the motor being in some cases connected directly to the 15 main shaft and in others by the interposition of a flexible shaft as may be desired.

The object of the invention is the construction of a massage machine having few 20 working parts and these of a strong and durable nature.

A further object is to reduce friction of 25 the working parts to a minimum, particularly when pressure is applied to the brush and to provide a simple and inexpensive device for general domestic use.

The various features of novelty which characterize the invention are pointed out with particularity in the claims annexed to and forming a part of this specification. 30 For a better understanding of the invention, however, and the advantages possessed by it, reference may be had to the accompanying drawings and descriptive matter in which I have illustrated and described one of the 35 forms in which my invention may be embodied.

Of the drawings, Figure 1 illustrates a 40 side elevation of a massage machine embodying my invention. Fig. 2 is a longitudinal section of the same showing the internal construction of the device and the manner of operating the main shaft by a flexible shaft connection. Fig. 3 represents a vertical section taken through the body of 45 the massage machine as indicated at 3-3 in Fig. 2. Fig. 4 is a detached side elevation of one of the working parts adapted to support the brush.

A is the cylindrical casing of the machine 50 and is provided with an inclined stem A¹ which is detachably secured to a handle A² by a pin a².

B is the main driving shaft of the machine 55 fitted to a reduced portion A³ of the casing and having a grooved head B¹ to receive a row of balls b, b, etc., which are

interposed between the head and a similarly grooved collar C. The shaft B together with the head B¹ is provided with an eccentric hole B² to receive a secondary shaft D, 60 one end of which is threaded at D¹ to receive a brush G. The shaft D which constitutes the brush holder is also provided with an enlargement D², which rests in a corresponding opening in the head B¹ and 65 serves as a bearing for a row of balls arranged between the enlargement D² and the head B¹ of the shaft B. The enlargement D² of the shaft D has a hole D³ to receive a rod E, which serves to prevent the shaft D 70 from turning when the machine is in operation. The rod E is provided with a spherical head E¹, which rests in a socket F¹ of a collar F. In order to take up lost motion between the head E¹ and socket F and 75 thereby prevent undue vibration, the rod E is bored out and fitted with a pin E² which under the influence of a spiral spring S is caused to bear against the casing A. To the threaded end D¹ of the shaft D, is fitted a 80 brush G, which may be of any desired shape, the form shown however consisting of a rubber disk provided with a number of pins, G¹, G², etc., and having a metal hub G², internally threaded to the portion D¹ of the 85 shaft D.

The machine is preferably operated by means of a flexible shaft H, although if desired the motor or other source of power may be directly connected to the shaft B. 90 I prefer, however, to operate the machine from the source of power by means of a flexible shaft H as shown in Figs. 1 and 2, one end of which is connected to the shaft by entering an opening B³ therein and being 95 held in place by a set screw b³. Surrounding the flexible shaft H is a cover I, threaded to a sleeve J, which is secured to the casing A by a coupling K.

Having described my invention what I 100 claim as new and desire to secure by Letters Patent is:—

1. A massage machine, comprising a casing, a main shaft, a secondary shaft journaled within the main shaft, a massage implement attached to the secondary shaft a fulcrumed rod passing through the secondary and adapted to prevent the same from turning, and a spring pressed pin interposed between the rod and casing of the machine. 105

2. A massage machine, comprising a casing, a main shaft, a secondary shaft carried

- by the main shaft and adapted to move in a path eccentric to the main shaft, a massage implement attached to the secondary shaft a rod adapted to pass through an opening in the secondary shaft, a collar mounted within the casing and having a socket to receive one end of said rod and a spring pressed pin interposed between the rod and the casing of the machine.
- 10 3. A massage machine, comprising a casing, a main shaft, a grooved collar located within the casing, a grooved head formed upon the main shaft, a series of balls or rollers interposed between said collar and

said head, a secondary shaft eccentrically mounted within the main shaft, a massage implement attached to the secondary shaft a row of balls interposed between the main shaft and secondary shaft, a rod fulcrumed to the casing and passing through an opening in the secondary shaft to prevent the secondary shaft from turning. 15 20

In testimony whereof I affix my signature in presence of two witnesses.

EDWARD E. ZIEGLER.
